UNITED STATES PATENT OFFICE.

JOSEPH BRISTOW, JR., OF OAK PARK, ILLINOIS.

STUCCO CONSTRUCTION.

1,110,309.

Specification of Letters Patent. Patented Sept. 15, 1914.

Application filed March 8, 1912. Serial No. 382,566.

To all whom it may concern:

Be it known that I, Joseph Bristow, Jr., a citizen of the United States, residing at Oak Park, in the county of Cook and State of Illinois, have invented certain new and useful Improvements in Stucco Construction, of which the following is a specification.

This invention relates to improvements in methods of constructing the walls of buildings by what is commonly known as the stucco process and relates particularly to means for connecting the cement plaster or mortar and reinforcing metallic lathing or fabric commonly used with such mortar or plaster.

The especial object of the improvements which form the subject matter of this application is to provide a furring strip or member adaptable for economical manufacture and easy application to the studding or walls of a building; also to provide quick and economical means for attaching the expanded metal or lathing to the furring strips, and to provide such construction and arrangement of means that any settling of the walls of the building will have a minimum effect on the stucco work, and any expansion and contraction of said walls will not tend to crack the plaster or mortar.

In stucco work of the class described, it is important for economical reasons to be able to erect the furring strips quickly and easily with unskilled labor and then to attach the expanded metal or lathing to the furring strips with equal facility and economy; and it is also extremely desirable to be able to stretch the expanded metal when it is being applied to the furring strips. Owing to the unequal expansion and contraction of wood and metal it becomes desirable to provide for lateral as well as longitudinal movement of the frame work of a building and also of the stucco coating applied to such building. An important object, therefore, of my invention is to provide for these conditions and conserve other advantages which will be apparent to those skilled in the art from an inspection of the accompanying drawings and specification.

In the drawings, I have illustrated a preferred adaptation of my invention in the following views:

Figure 1 shows in elevation, portions of two furring strips with a section of expanded metal lathing attached thereto in

the manner contemplated by my invention; Fig. 2 is a cross sectional view taken through a portion of a stud with my improved furring strip attached thereto; Fig. 3 is a view similar to Fig. 2 but showing a slightly modified form of furring strip.

Referring to the details of the drawings, 4 represents my improved furring strip, which consists of a length of sheet metal bent into substantial U-shape in cross-section but with the middle bend flat and with the edges rebent to form curved flanges as 4^a, projecting outwardly from the sides 4^b, the latter being slightly divergent, as clearly shown in Fig. 2. At intervals throughout the length of the strip are elongated slots 4^c, which are adapted to receive the nails 5 by which the furring strips are secured to the studs 10 of a building. The nails 5 are of the usual steel wire type with a round head 5^a and adapted to be readily bent.

The furring strip shown in cross section in Fig. 3 is similar in general construction to the form shown in Fig. 2 but the sides 70 11 are curved outwardly and the flanges 11^a are somewhat larger than the flanges 4^a of the strip 4.

In carrying out my invention, the furring strips will be attached to the face of the wall at such intervals as may be necessary to properly support the expanded metal lathing, and may run either longitudinally with the studs or transversely as may be desired. The metal lathing may be of any type in which there are openings large enough to permit the easy passage of the heads of the nails 5. The form of expanded metal shown in the accompanying drawing, designated by the reference character 6, is a well known form of such product, and is especially adapted for use in connection with my improved furring strips and attaching means. With the furring strips in place and the nails driven through the slots 4^a so that the head of the nail and portion of the shank adjacent thereto projects outwardly at right angles to the face of the furring strips, the workman will apply the expanded metal by placing it over the heads of the nails, stretching it at the same time so that it will lie as flat as possible, and will then bend the nails over at right angles as shown in Fig. 1, thus tying the metal lathing to the furring strips.

In carrying out my invention the studs may have applied thereto the usual layer of

boards as 9, and building paper as 8, and the thickness of the furring strips or distance from the flanges 4^b to the flat outer face or bend, will be sufficient to permit the 5 mortar or plaster 7 to form perfect ties or clenches on the rear side of the lathing 6, and at the same time leave an interval or space for the circulation of air between the plaster and the paper sheathing 8.

10 It will be noted that the length of the slot 4^a is several times greater than the cross diameter of the nails 5, so that any longitudinal movement of the studs or frames in which the nails are secured will not necessarily 15 cause a like movement in the furring strips, as the cross diameter of the slots 4^a will be sufficient to permit a sliding action of the furring strips over said nails.

It will also be noted that the openings 20 in the metal lathing are sufficiently larger than the cross diameter of the nails 5 to permit more or less movement of the metal lathing both vertically and laterally without transmitting said movement to the furring strips.

In the form of furring strip disclosed in Fig. 3, the curved wall 11 will permit expansion and contraction of the stucco coating toward and away from the structure, it being understood that the furring strips are made of thin sheet metal having a certain amount of resiliency or spring. The curved flanges 4^b, 11^a, form a bearing for the edges of the furring strips which 35 will permit expansion or contraction of the strips and at the same time will not tear the paper, against which they bear. The flat face of the furring strip midway its edges affords a wide bearing for the portion of 40 the metal lathing engaging said face and thus tends to sustain the lathing in flat relation to the adjacent structure and to the mortar in which the lathing is embedded.

It is obvious that instead of using wire 45 nails and bending them to form hooks, I may use wire hooks in the first instance. It

is also evident that if the heads of the nails are almost as large as the apertures in the metal lathing, or the nails be driven at an angle so as to incline downwardly from 50 their heads, it may not be necessary to bend the nails at all, hence I do not wish to be limited to any special form of furring strip and metal lathing attaching devices, as any style may be used that will serve as a common holding means for both furring strips and lathing while permitting the relative movements described as incident to the settling of the building or the expansion and contraction of the materials which enter 55 into the stucco work or construction.

From the construction set forth, it will be noted that the metallic lathing is so flexibly anchored to the furring strips that up and down or lateral movements of the latter 60 will not affect the plastic coating on the lathing in the same degree as if the lathing was tied to the furring strips in the manner usually practiced.

Having thus described my invention, what 70 I claim as new, is:—

Means for attaching plastic material to a supporting structure, consisting of a sheet metal furring member having an outer bearing face and outwardly curved edges, 75 and with slots formed in said bearing face, nails passing through said slots and adapted to engage the supporting structure to hold said strips in place, portions of said nails projecting beyond the bearing face of 80 said strips and bent into hook form, and perforated metal lathing applied to the bearing face of said strips and adapted to engage said nails and to be engaged by the bent over portions of said nails.

In testimony whereof I affix my signature in the presence of two witnesses.

JOSEPH BRISTOW, JR.
